CLAIM

The ornamental design for a combined decanter and stopper, substantially as shown and described.

DESCRIPTION

FIG. 1 is a front elevational view of combined decanter and stopper showing my new design;

FIG. 2 is a rear elevational view;

FIG. 3 is a side elevational view, the opposite side being a mirror image of the side shown;

FIG. 4 is a top plan view; and

FIG. 5 is a bottom plan view.

FIG. 1

FIG. 2

FIG. 5

FIG. 4

FIG. 3
